HOUSING FOR MOUNTING A SEALED BEAM HEADLAMP

Peter Hedgewick, Windsor, Ontario, Canada, and Jay E. White, Jr., Bloomfield Hills, Mich., assignors to Reflex Corporation of Canada Limited, Amherstburg, Ontario, Canada, a corporation of Ontario

Filed Apr. 29, 1968, Ser. No. 11,677

Term of patent 14 years

(Cl. D48—32)

FIG. 1 is a front elevational view of the housing for mounting a sealed beam headlamp embodying our novel design.

FIG. 2 is a side elevational view taken from the right as viewed in FIG. 1.

FIG. 3 is a rear elevational view.

FIG. 4 is a side elevational view taken from the right as viewed in FIG. 3.

FIG. 5 is a sectional view taken along the line 5-5 in FIG. 3.

We claim:

The ornamental design for a housing for mounting a sealed beam headlamp, as shown and described.
